UNITED STATES PATENT OFFICE.

ELIZA INGLE, OF BALTIMORE, MARYLAND.

SCALE.

1,356,987.

Specification of Letters Patent. Patented Oct. 26, 1920.

Application filed March 21, 1919. Serial No. 284,021.

To all whom it may concern:

Be it known that I, ELIZA INGLE, a citizen of the United States of America, residing in the city of Baltimore, State of Maryland, 5 have invented certain new and useful Improvements in Scales, of which the following is a specification.

This invention relates to a scale particularly adapted for use by people who are 10 blind or otherwise possessed of defective sight, though it is capable of being variously applied in the arts where a scale is to be used under circumstances where ocular reading is inconvenient or impossible.

15 In its preferred form the scale consists of a bar or rod or other convenient member having an exposed edge marked with notches or lines perceptible to the touch and regularly spaced by the chosen unit of measurement. Parallel to this edge is a groove, the edge of the groove remote from the first-mentioned edge being divided by similar notches or depressions spaced by units which are convenient fractions of the spaces 20 separating the first set of markings or notches, and spaced from this groove preferably by a similar margin is a second groove beyond which is still another set of notches or graduations evenly spaced by 25 fractions of the units in the next preceding scale. This arrangement may be continued until the desired minimum fractional unit of measurement is attained. In measuring, the finger is run along the edge until the 30 desired number of the larger units is counted, then along the first groove to the desired number of the larger fractions, etc.

35 As the commonest use of this scale up to the present point of its development has 40 been in connection with a cutting-board in the bookbinding art, it has been illustrated as applied to such a cutting-board having the usual guillotine knife, though it is capable of various applications.

45 In the accompanying drawing I have illustrated a scale embodying my invention. In the drawing—

Figure 1 is a perspective of the scale applied to a cutting-board.

50 Fig. 2 is a fragmentary end view of the same.

Fig. 3 is a fragmentary view of the scale in perspective including a marker or abutment for use in cases where repeated measurements of the same extent are to be made,

as with the cutting-board where a number of pieces of the same size are to be cut.

Fig. 4 is an end view of the scale with the abutment.

Referring to the drawings by numerals, I 60 have illustrated a triangular scale 1 having arranged along the top edge 1' notches or markings or graduations 2 of a nature to be detected by the touch, the same being spaced one inch apart and preferably design- 65 nated by raised points or dots 3 arranged according to an accepted and well-known numerical system or cipher taught in institutions for the blind. Spaced from the edge 4 by a suitable interval which may be about 70 a quarter of an inch and parallel to the edge is a groove 5. In the present instance the markings or graduations 2 extend across the space 6 between the edge and the groove, and terminate at each end in notches 7 conveniently detected and located by running the finger nail along either edge 4 or 8. Beyond the groove 5 and parallel thereto is still another groove 9, the spacing being 75 preferably similar to that between the edge 80 4 and the groove 5. Any desired number of grooves may be used, the last groove being preferably spaced by a similar interval 10 from the lower edge 11 of the graduated face of the scale. The interval or space 12 85 between the grooves 5 and 9 is marked with graduations 13 similar to the graduations 2 and likewise terminating at each end in notches 7 in the respective edges of the two grooves. These graduations or markings 90 are spaced by convenient fractions of these units relating to the graduations on the upper edge. In this instance the markings are one-half an inch apart, and the flat surface between the lower groove 9 and the bot- 95 tom edge of the face of the scale 11 is graduated in still smaller fractions of an inch. In this instance these markings are an eighth of an inch apart and terminate adjacent the groove in notches 7 formed in the edge of the groove. For convenience in distinguishing the smaller graduations, I 100 have shown the markings as terminating in notches in every second graduation, only, that is the quarter inches are marked with 105 notches and the intervening eighth inch spaces are marked with cuts 14 having no notch. This detail is, of course, not essential. The scale has been shown in Fig. 1 in connection with a cutting-board 15 and a guillo- 110

tine cutting knife 16. In Fig. 2 the cutting-board is shown in edge or side elevation, and means for fastening the scale to the cutting-board in the form of a screw 17 is also shown. In Figs. 3 and 4 I have shown a sliding abutment or marker 18 held in position by a removable pin 19 engaging holes 20 spaced by a distance corresponding to the smallest unit to which the scale is graduated.

In reading the scale the finger is run along the top edge 1' or the surface 6 intervening between the top edge and the top groove until the graduation marking the desired number of inches is reached and located. With the finger nail on this graduation, the finger is passed down to the first groove and moved along until the nail encounters the half-inch mark provided a fractional measurement of over a half-inch is desired. When the half-inch mark intended is located, with the nail in this mark the finger is passed to the next groove if the measurement is to be in units of an eighth of an inch and the desired number of eighths is measured, the contact of the nail with the notches at the bottom edge of the groove 9 serving as an index for counting these notches. When the desired number of eighths has been counted, the reading of the scale is complete. If a piece of paper or card-board of this dimension is to be cut, an edge of the card-board is laid on the cutting-board in contact with the lower edge of the scale, the corner being in engagement with the finger nail which is in the notch indicating the desired measurement. If the card-board is large enough, the edge to be cut will overlap the edge of the cutting-board and by a stroke of the guillotine knife the card-board is cut to the desired dimension.

It may be considered more convenient in making such measurements to move the abutment 18 to the desired point determined as just described, fasten it by the pin 19 in the corresponding hole 20 and place the corner of the paper or whatever is to be cut

against this abutment and the lower edge of the face of the scale which is beveled at 21 for this purpose to cut the overlapping edge or edge portion of the paper as above.

Having thus described a tool or scale embodying my invention specifically in order that it may be made and used by those skilled in the art, I would have it understood that I do not intend to limit my invention to the details thus described.

What I claim and desire to secure by Letters Patent is:

1. A scale having an elongated measuring surface provided with graduations thereon consisting of transverse notches crossing said surface and spaced by the desired units of measurement, the scale having a groove bordering said surface and a similar surface on the opposite side of the groove, said second surface being provided with graduations consisting of transverse notches in said surfaces and spaced by fractions of the said unit the two series of graduations being so related that the notches indicating corresponding points in the two series are directly in alinement.

2. A scale having an elongated measuring surface, graduations thereon consisting of transverse notches crossing said surface and spaced by the desired units of measurement, the scale having a groove bordering said surface and a similar surface on the opposite side of the groove, graduations on said second surface consisting of transverse notches crossing said surface and spaced by even fractions of the said unit the two series of graduations being so related that the notches indicating corresponding points in the two series are directly in alinement, and markings notable by touch distinguishing the various graduations.

Signed by me at Baltimore, Maryland, 90 this 18th day of March, 1919.

ELIZA INGLE.
